(57) **CLAIM**

The ornamental design for a double closed cheese & charcuterie board, including individual trays, as shown and described.

DESCRIPTION

FIG. 1 is a perspective view of the double closed cheese and charcuterie board including individual trays, shown in a position of use;

FIG. 2 is a perspective view of the double closed cheese and charcuterie board including individual trays;

FIG. 3 is a top view thereof;

FIG. 4 is a bottom view thereof;

FIG. 5: is a side view thereof, shown in an environment of use;

FIG. 6: Cross section view of FIG. 5; and,

FIG. 7: Side view of FIG. 1.

Line shading is used in the accompanying figures to convey surface shading and contouring.

The broken lines depict portions of the double closed cheese & charcuterie board, including individual trays that form no part of the claimed design.
